UNITED STATES PATENT OFFICE.

JOSEPH A. MUMFORD, OF HANTSPOST, NOVA SCOTIA, CANADA.

BARREL-HEAD-SAWING MACHINE.

SPECIFICATION forming part of Letters Patent No. 417,071, dated December 10, 1889.

Application filed January 14, 1889. Serial No. 296,269. (No model.)

To all whom it may concern.

Be it known that I, JOSEPH A. MUMFORD, of Hantsport, Nova Scotia, Canada, have invented certain new and useful Improvements in 5 Barrel - Head - Sawing Machines; and I do hereby declare the following to be a full, clear, and exact description of the same, reference being had to the accompanying drawings, forming a part of this specification, and 10 to the letters of reference marked thereon.

This invention relates to an improvement in machines for sawing and beveling barrel-heads, such as are commonly known as "heading-turners," and has for its object to produce 15 a simple, cheap, and effective machine adapted to saw barrel-heads of varying sizes and be easily and readily operated by an ordinary workman or person not skilled in handling such machines.

20 To these ends the invention consists in a barrel-head turner having the saw and arbor mounted in a casting or table adjustably secured to its support or post in order to change the angle of the machine, and a frame or casting adjustably secured to said first-mentioned table, and carrying a swinging frame, in which the barrel-head is clamped, with means for giving the head-clamping mechanism the necessary rotation for bringing every 25 part of the periphery of the head into co-operation with the saw, as will be presently explained.

The invention further consists in certain 30 novel details of construction and arrangement and combination of parts, as will be hereinafter described, and pointed out in the claims at the end of this specification.

In the accompanying drawings, Figure 1 is 35 a perspective view of a heading-turner constructed in accordance with my invention. Fig. 2 is a top plan view of the same; Fig. 3, a side elevation; and Fig. 4 a front elevation, showing the barrel-head clamped in position. Fig. 5 is a sectional view on the line $x-x$, Fig. 2.

40 Similar letters of reference in the several figures indicate the same parts.

The main casting A, or table in which the bearings $a-a$ of the saw-arbor shaft B and 45 driving-pulley C are located, is provided with

means for adjustably securing the same upon any suitable support—such as a post D or a bracket extending from the side walls of the building—such adjustable fastening means preferably being formed by the curved bearing 55 d , held in position by the eyebolt d^3 , pivoted on a cross-belt d^5 in the bracket or post and capable of swinging in the slot d^4 , (shown in dotted lines, Fig. 3,) although other well-known forms of adjustable connections may be employed. The saw-arbor shaft B is preferably located to one side of the support and extends way through both bearings $a-a$, the saw being mounted on one end and a pulley a' on the opposite end for driving the head-clamp. The drive-pulley C, for the sake of economy and compactness, is mounted between the bearings $a-a$.

A casting or frame E is mounted on the table A at one side, and adjustably connected thereto by means of the bolt e , working through slots e' in said casting, suitable guides or ways e^2 being provided to maintain the proper alignment of the castings, although, as is obvious, two or more bolts and 75 slots may be employed to accomplish the same results.

Journals F F are formed in the rear portions of the table A and frame E, in which the shaft f takes its bearing, a pulley f' , driven 80 by belt f^2 from the small pulley a' , being mounted on one end of the shaft, and a small gear or friction wheel F^3 , near the opposite end, as shown in Fig. 2.

At the side of the frame or casting E, or 85 at right angles to the journals F, are formed journals G G, one at the front and the other at the rear of the frame, in which journals a shaft H takes its bearings, the gear or friction wheel h on its rear end engaging the small wheel F^3 on the shaft f .

Below the shaft H, and preferably with said shaft as a center, is suspended a bifurcated frame I, between the two arms $i-i'$ of which are located the clamps K K' for holding the barrel-head. Both clamps K K' are mounted in bearings in the ends of the arms $i-i'$, so as to be capable of a rotary motion, the shaft carrying the upper clamp having the bevel-gear L at the upper end, with 90 95 100

which engages the small bevel-gear l on the end of shaft H , whereby the said clamp is rotated by motion derived from the saw-arbor shaft through the instrumentalities mentioned.

In order now to bring the two clamps together, the lower one K' is made adjustable vertically, and a small cam or lever k , having an operating-handle k' , is located below the lower end of its supporting-shaft. Thus when said cam is turned the clamp K' is elevated and the two clamps brought together. I preferably employ projections K^2 on the lower clamp to assist in centering the head and to insure its rotation without danger of being thrown out of position, and, if desired, similar projections may be employed on the upper clamp, particularly where the head is very heavy.

As before intimated, the frame I is pivotally hung below the frame E , with the shaft H as a center of oscillation, and the bearing on which the frame turns may, if desired, be formed by said shaft, as shown in the drawings, the shaft being simply passed through a sleeve M on the upper portion of the frame; or, if desired, the bearings may be formed by projections from the journals G , similar in all respects to the ordinary well known cone bearing.

The saw N is preferably of the concave form universally employed in this class of machines.

The operation will now be readily understood. The board from which the head is to be formed or the partially completed head is placed on the lower clamp and properly positioned and centered. Said clamp, it will be particularly observed, is stationary and of sufficient area to give the proper support to the head. The cam-lever is then swung around, and the clamp, with the head, is raised bodily and the head brought into contact with the upper revolving clamp, which first operates to press the head against the points on the lower clamp, and finally imparts thereto its rotary motion. The entire frame is swung toward the saw, as indicated in dotted lines, Fig. 4, and as the head is presented at an angle to the plane of the saw the proper bevel to fit the chine of the barrel is cut, and the head being revolved constantly in relation to the saw gives the necessary circular circumferential shape. If desired, the handle k' may be grasped by the operator to swing the frame up to the saw; but it is obvious that any of the well-known foot-lever arrangements may be employed to accomplish the same result, or, for that matter, a foot-lever may be employed to force the lower clamp up, as well as to swing the frame toward the saw, as will be readily understood by those skilled in the art.

As it may be desirable in some instances to incline the clamps, as well as the saw and frame, it may be easily accomplished by loosening the bolts connecting the table A to the

standard, shifting the table on its curved bearing, and setting the bolts up tight to hold the parts in adjusted position.

The saw-arbor shaft may be provided with a fast and loose pulley, as shown in Fig. 1, to which the drive-belt is applied, whereby the operator may easily start or stop the saw by shifting the belt.

It is obvious that the machine is susceptible of considerable alteration and modification without departing from the spirit of my invention, and I do not wish to be understood as limiting myself to the exact construction shown, and while in the machine shown I rely entirely upon the weight of the swinging frame and head-clamps to carry them away from the saw it is obvious that additional weight or springs may be employed to supplement such action, although these are, as a rule, found unnecessary. If desired, also, the lever for raising and lowering the lower clamp may be so constructed as to release the clamp when not held by the operator. Thus not only will the frame be returned to normal position, but the clamp will be released by gravity.

Having thus described my invention, what I claim as new is—

1. In a heading-turner, the combination, with the saw, of the substantially horizontal clamps for the head, movable to and from the saw, consisting of the upper constantly-rotating clamp and the free lower clamp on which the head is placed, whereby the head may be properly positioned and centered before being caused to rotate, substantially as described.

2. In a heading-turner, the combination, with the saw, of the substantially horizontal clamp for the head, comprising the upper constantly-rotating clamp and the lower free clamp, a frame swinging below a fixed center toward and from the saw, and bearings in said frame for the clamps, whereby the head may be positioned on the lower clamp before being rotated and presented to the saw, substantially as described.

3. The combination, with the saw-arbor shaft and the table in which it takes its bearings rigidly mounted on the supporting-post, of the frame adjustably connected to said table and carrying the head-clamps, whereby said clamps may be adjusted with relation to the saw for the accommodation of heads of different sizes, substantially as described.

4. The combination, with the saw-arbor shaft, the table in which it takes its bearings rigidly mounted on the supporting-post, and the frame adjustably connected to said table, of the gravitating head-clamps pivotally mounted on said frame and adapted to swing to and from the saw, whereby the clamps may be adjusted with relation to the saw for the accommodation of heads of different size, substantially as described.

5. The combination, with the saw-arbor shaft, the table on which it is mounted, and the pivoted head-clamps supported by said

table and adapted to swing to and from the saw, of the supporting base or post and an adjustable connection between said table and base or standard, whereby the inclination of 5 the table, saw, and clamps may be varied, substantially as described.

6. The combination, with the saw and oscillating frame moving in a substantially vertical plane and having the rotating upper 10 clamp mounted in fixed bearings in the frame, of the lower clamp mounted in bearings in said frame and adjustable to and from the rotating clamp, substantially as described.

7. The combination, with the table having 15 the saw and drive-pulley mounted thereon, the swinging frame connected thereto, the rotary clamps mounted in said frame, and the gear-wheel on the upper clamp, of the shaft on which the frame pivots, having the gear- 20 wheel engaging the wheel on the clamp and

connected to the driving mechanism, substantially as described.

8. The combination, with the table and frame adjustably connected thereto, the saw-arbor shaft mounted on said table, and the 25 swinging frame mounted on said adjustable frame and carrying the head-clamps, of the shaft having bearings on both said table and frame, with the pulley and belt driven from the saw-arbor shaft, and the shaft forming 30 the pivot for the swinging frame, having the gear-wheel engaging the gear on the head-clamp and gearing connected to said last-mentioned shaft and the shaft driven from the saw-arbor shaft, substantially as de- 35 scribed.

JOSEPH A. MUMFORD.
